HERMAN HARDER, OF BELLINGHAM, WASHINGTON.

RELEASABLE STAKE FOR LOGGING-CARS.

1,077,246.

Specification of Letters Patent. Patented Oct. 28, 1913.

Application filed June 17, 1913. Serial No. 774,170.

To all whom it may concern:

Be it known that I, HERMAN HARDER, a subject of the King of Great Britain, residing at Bellingham, in the county of Whatcom and State of Washington, have invented certain new and useful Improvements in Releasable Stakes for Logging-Cars, of which the following is a specification, reference being had therein to the accompanying drawings.

This invention relates to an improvement in the construction of a logging car, and the principal object of the invention is to provide an improved log support, and an improved stake for holding the logs in place.

Another object of the invention is to so mount the stake that the stake may be released from the opposite side of the car, thus preventing any danger of the workmen being hit by the logs rolling from the car and injured.

Another object of the invention is to provide an improved means for holding the bunks in spaced relation.

Another object of the invention is to provide a log support which may be formed from old railroad rails, thus permitting the rails which are of no further use to the railroad to be put to a new use, and thus a great saving accomplished.

With these and other objects in view this invention consists of certain novel combinations, constructions, and arrangements of parts as will be hereinafter fully described and claimed.

In the accompanying drawings:—Figure 1 is a perspective view showing one form of the invention. Fig. 2 is a section along the line 2—2, in Fig. 1, certain portions of the device being omitted. Fig. 3 is a section similar to Fig. 2 and taken along the line 3—3, in Fig. 1. Fig. 4 is a fragmentary longitudinal sectional view through one end portion of the log support shown in Fig. 1. Fig. 5 is a perspective view of the log support formed in a manner similar to that shown in Fig. 1, but using a pair of railroad rails. Fig. 6 is a section along the line 6—6, in Fig. 5. Fig. 7 is an enlarged perspective view of the device for holding the bunks in spaced relation. Fig. 8 is an enlarged perspective view of one of the stakes.

In the accompanying drawings the numeral 10 indicates the flooring of a flat car, one end portion only of the car being shown. At each end of the car the bunks 11 and 12

are placed transversely and secured by any desired means. Protecting plates 13 are placed along the bunks to protect the bunks from wear, and the bunks are held in spaced relation by the angle members, one of which is shown in perspective in Fig. 7. Each of these angle members may be cast, or formed from a strip of heavy sheet metal bent to form the inner wall 14 and outer walls 15 and 16, which are connected with the opposite end portions of the inner wall by the connecting walls 17 and 18. The angle members are placed between the bunks and are held in place by the securing bolts 19 which pass through openings 20 in the outer walls 15 and 16 and through the bunks as shown in Fig. 4. A stake 21 is pivotally mounted upon a pin 22 passing through openings 23 in the inner and outer walls 14, 15 and 16, which pin also passes through the bunks and thus forms additional securing means for the angle member. A chain 24 is connected with the eye 25 of the stake and is adapted to be drawn through a circular opening 26 formed in the end wall 17.

In Figs. 5 and 6 there has been shown a modified form of the device in which a pair of rail sections 27 and 28 are used in place of the bunks 11 and 12. The rail sections are riveted to a base plate 30 by means of the rivet 31 and the base plate is secured to the flooring of the flat car by any desired means. Spacing bolts 33 extend between the rails 27 and 28 and are held in place by the inner and outer nuts 34 and 35, thus bracing the rails and preventing the central portions of the rail from spreading or moving toward each other. The angle members are placed between the end portions of the rail and fit against filling blocks 35', which blocks are provided to form firm supports for the outer walls 15 and 16 of the angle members. When this car is in use the chains are released from the hooks and the stakes lowered. A log is then placed upon the bunks and the stakes upon one side raised to the desired position and held in this position by drawing the chains tight and securing them with the hooks. The remaining ones of the lower row of logs are now put in place and the stakes upon the opposite side of the car are then raised and the chains tightened to hold them in the raised position. The upper logs are put in place and rest between the lower logs so that the pile of logs will not slip from the car. The

logs are removed from the car by releasing the chains to let the stakes upon one side of the car drop, thus permitting the logs to roll from the car.

5 Having thus described the invention what is claimed as new, is:—

1. A device of the character described comprising a pair of bunks, angle members holding said bunks in spaced relation, each 10 of said angle members comprising an inner wall and a pair of outer walls positioned upon opposite sides of said inner wall, walls connecting the opposite ends of said outer walls with said inner wall, a pivot pin passing through said bunks and the inner and outer walls of said angle members, a stake pivotally mounted upon said pin, and a chain having one end connected with said stake and having its other end adapted to be 15 passed through an opening formed in one of the end walls of the angle member at the opposite end of said bunks whereby said stake may be drawn inwardly and held in the adjusted position, and means for engaging said chain to hold the stake in an adjusted position.
- 20 2. A log support comprising a base plate,

a pair of railroad rails mounted upon said base plate, rods connecting said railroad rails intermediate their length to hold the 30 same in spaced relation, angle members placed between the end portions of said rails, filler blocks placed between said angle members and the webs of said rails, a pivot pin passing through each of 35 said angle members and through the end portions of said rails, and a stake pivotally mounted upon each of said pivot pins.

3. In a device of the character described, a 40 bracing and spacing angle member comprising outer walls, an inner wall between said outer walls, end walls connecting the opposite ends of said outer walls with said inner wall, one of said end walls being of less height than said inner and outer walls, and 45 the remaining end wall being provided with an opening.

In testimony whereof I hereunto affix my signature in presence of two witnesses.

HERMAN HARDER.
